TUBE SOCKET

Alvero C. Gregson, Garden City, N.Y., assignor to Instruments For Industry, Inc., Hicksville, N.Y., a corporation of New York

Filed Apr. 13, 1960, Ser. No. 22,052

2 Claims. (Cl. 339—91)

This invention relates to sockets for ultra-high frequency tubes and the like and more particularly to sockets for tubes having coaxial longitudinal displaced electrode terminals.

Many different types of tubes designed especially for use in ultra-high frequency circuits are provided with one or more electrodes in the form of radially extending circular flanges. In addition, it is not uncommon to provide other electrode terminals for such tubes in the form of coaxial, longitudinally displaced cylinders so that the tubes are especially suited for use with coaxial transmission line circuit elements. However, the characteristics of these so-called coaxial tubes that permit their use at very high frequencies also make them desirable for use in other types of circuits that do not employ coaxial transmission lines. In particular, the low inter-electrode capacitance and high transconductance common to such tubes make them very useful in grounded grid circuits employing so-called lumped constants.

Sockets that are formed in such a way as to permit coaxial tubes to be used in lumped constant circuits encounter four problems. In the first place they must provide adequate electrical contact to the various electrodes to minimize the impedance encountered by electrical current in reaching and leaving the electrodes. In the second place the socket structure must be sufficiently rugged to stand the use to which it will be put. Normally this requires that the socket withstand severe mechanical shocks in order to be suitable for use in military equipment, even though the socket may also be used in non-military equipment. Thirdly, the socket must permit easy insertion and removal of the tube itself. And, finally, the socket must be so constructed as not to mitigate the desirable features of the tube by introducing high interelectrode capacitances or lead inductances, which would reduce or altogether remove the advantage to be obtained from using tubes having low electrode capacitance and low lead inductance.

It is a principal object of the present invention to provide a socket meeting the foregoing criteria.

The means by which this and other objects are realized will be described in greater detail in connection with the drawing in which:

FIG. 1 shows a cross-sectional view of a front elevation of a socket constructed according to the invention;

FIG. 2 shows a perspective view in section, of the socket in FIG. 1; and

FIG. 3 is a perspective view of the tube mounting plate of the socket shown in FIGS. 1 and 2.

Basically, the socket of the invention comprises a plate having a hole through which one end of the tube is inserted. The hole is large enough for the body of the tube, adjacent to one tube flange, to extend through it, and resilient spring contact fingers are attached on one side of the plate surrounding and extending partly over the hole to make connection with the flange and to prevent the tube from passing entirely through the hole in one direction. A cover plate is attached, at least partly by snap fastening means, to the other side of the main plate to hold the flange of the tube firmly in place against the resilient contact fingers. In addition, resilient contact members, supported by insulators, are spaced adjacent to the location of the main plate so as to connect with

2

the various tube terminals other than the one held by the plate.

Referring to FIG. 1, a type 6442 tube is indicated, generally, by the reference character 11. This tube comprises an anode 12 having heat dissipating flanges 13, the flanges 13 being removable and not part of the tube 11; a control grid terminal 14 in the form of a radially-extending flange; a tubular cathode contact terminal 16 coaxial with the anode 12 and the grid 14; and two heater terminals 17 and 18, which are also concentric, or coaxial, with the other terminals of the tube. The heater terminal 18 is covered by a removable jacket to make better contact with the heater terminal, the jacket not being part of the tube. The base plate of the socket is indicated by the reference character 19, and this plate is provided with an aperture 21. A conductive ring 22 is attached to one side of the plate 19 surrounding the aperture 21 to provide spacer means for properly locating a ring 23 composed of resilient, conductive material, such as gold-flashed beryllium-copper, and formed with inwardly extending contact fingers. An annular ring 24 holds the ring 23 in place against the spacer 22 and further acts as a shield closely surrounding the reduced diameter portion 26 of the grid terminal 14 to prevent electro-magnetic coupling between the anode terminal 12 and the cathode 16.

On the other side of the plate 19 is a cover plate 27 attached by means of a hinge 28 to the surface of the plate 19. The cover plate 27 is preferably bifurcated and its extremities are provided with snap-fastening fingers 29 which extend through a pair of lower apertures 30 in the plate 19. The fingers 29 interlock with rolled-over edges 31 of the apertures 30 to hold the cover plate firmly in place against one surface of the grid flange 14.

The base plate 19 of the socket is supported on a conductive plate 32 and is positioned in a slotted, or channelled, guide, the side members of which are indicated by reference characters 33 and 34 and the base member of which is indicated by reference character 36, which if desired can be made as one integral U-shaped member. A spring contact member 37 may be affixed to the plate 9 to lock over the member 36, which is affixed to the plate 32, in order to insure good electrical contact therewith.

An insulating support 38 carries a folded-over, resilient, serrated connector 39 in position to bear firmly against the anode terminal 12 in order to make proper electrical connection therewith. The serrated member 39 is carried in a slot in the upper side of the support 38 in order to assure that the member 39 will always be positioned in exactly a certain location with respect to the plate 19. The purpose of this is to insure that the main circuit constants will remain substantially identically the same each time the tube 11 is removed and a new tube is inserted, for only in this way can an ultra-high frequency circuit employing lumped-constant elements be properly set up.

A similar insulating support 41 carries three upright members 42-44 which in turn support and fixedly locate three resilient contact members 46-48. The contact members 47 and 48 may be in the form of simple resilient conductive straps, since they serve only to carry low frequency or direct current to the heater terminals 17 and 18 and are not required to carry high frequency current. The other contact member 46 is of the serrated type to make good high frequency contact with the cathode terminal 16 of the tube.

FIG. 2 shows a perspective view of the socket of FIG. 1 illustrating the arrangement of the insulating members 38 and 41 together with the contact members 39 and 46-48 held by them. The contact members 39 and 46

are provided with pairs of terminal tabs 49 and 51 respectively, at each end of the serrated sections, although one tab of each pair is shown in this cross-sectional view. The inductance of the contacts 47 and 48 is not as much a matter of concern, and so these latter contacts have only one tab, each, which is not shown in this cross-sectional view. The insulating members may be affixed to the base plate 32 in any convenient way, such as by rivets, one of which is indicated by reference character 52.

The ends of the two side members 33 and 34 of the slotted guide in which the base plate 19 is supported are attached to upwardly directed extensions 53 of the base plate 36. The members 33 and 34 are at right angles to the base member 36 to make it easy to insert the base plate 19 therein. Thus, in order to change the tube it is merely necessary to pull the base plate 19 out of the guide, open up the hinged cover plate 27, which allows the tube to be removed freely, place a new tube in the aperture 21, close the cover plate 27 and slip the base plate 19 back into the guide formed by the members 33 and 34. The members 33 and 34, or at least one of them, are resiliently biased toward each other to squeeze the edge of the plate 19 tightly and to make good electrical contact therewith.

FIG. 3 shows the plate 19 alone. The cover plate 27 is swung up out of the way to permit a tube to be inserted. One corner of the plate 19 is shown broken away to reveal the serrated resilient clip 37. This clip is held in place by several rivets 54 near the bottom of the plate. The top of the plate 19 is bent over, as indicated by reference character 56, to form a handle for pulling the plate out from between the guide members 33 and 34.

What has been described is a tube socket which is rugged and reliable and permits removal and replacement of the tube with positive seating assured each time. The socket permits quick replacement of tubes without disturbing any of the associated circuitry. This is accomplished by the use of spring contacts which are directly connected to the circuit and maintain their position in the molded plastic mount. The removal and replacement of the tube therefore cannot cause any shift of

4
circuit elements, which is extremely important in ultra-high frequency applications.

It is to be understood that only one embodiment of the invention has been described and that changes and modifications may be made thereto without departing from the invention.

What is claimed is:

1. A socket for an electron discharge device having at least one electrode terminal in the form of an outwardly extending metal flange, said socket comprising: a metal member having an aperture therein; a spring contact member attached to said metal member adjacent to and overlapping said aperture to bear firmly against one side of said flange; a resilient snap-fastening member attached to the opposite side of said plate and overlapping said flange to hold said electron discharge device in operative position against said spring contact member; and a U-shaped holder for said metal member, said U-shaped holder comprising a pair of resilient slide channels to hold the opposite edges of said metal member in firm contact.
2. The socket of claim 1 comprising, in addition, insulating members spaced from said U-shaped holder; and a plurality of resilient electrode terminal connectors supported by said insulating members in longitudinally spaced relationship to make connection with correspondingly longitudinally spaced electrode terminals of said electron discharge device.
